ATOMIZER FOR SPRAYING INSECTICIDE LIQUIDS AND THE LIKE

Constantino Lilienthal, Buenos Aires, Argentina

Application February 10, 1950, Serial No. 143,444
In Argentina July 26, 1949

3 Claims. (Cl. 299—88)

1

This invention relates to a new atomizer for spraying liquids and more particularly insecticide liquids and the like, of the kind that comprises a piston pump operated by hand.

To the knowledge of the inventor, the types of atomizers of this kind known to date, comprise a cylinder into which the piston runs, and a container for the liquid, fixed externally to an end of said cylinder. A tube taking out liquid from the container cooperates with another tube through which the pump expels air to atomize the liquid. The known atomizers are thus voluminous and easily subject to fracture, since it is difficult to attach the container firmly on the cylinder. When packed together for transport purposes they occupy too much space, due to their shape. Furthermore the liquid pours out from the container easily.

One object of this invention is to provide an atomizer or sprayer that has no external container; that occupies less space than the known sprayers do, and consequently may be packed more efficiently; that is of a simple construction and that permits to spray the liquid into places inaccessible to common sprayers.

Another object of the invention is to provide an atomizer from which container the liquid cannot pour out when the atomizer is not in use. Further objects of the invention will appear from the following description.

The atomizer I invented essentially consists of a cylindrical piston pump eccentrically fixed into, and to the wall of, another cylinder or casing of greater diameter; the space comprised between the cylinder pump and the external cylinder serving as container for the liquid. At one end of the external cylinder two chambers are formed: one that acts as a well fed with liquid by the container, and a second chamber from which the liquid is taken off for atomizing and into which the liquid in the chamber is forced by the action of the atmospheric pressure acting in the container and in the first chamber.

For the better understanding of my invention I accompany drawings in which two embodiments of the sprayer I invented are given as examples.

In these drawings:

Fig. 1 shows a longitudinal cross-section view of a first embodiment of my sprayer.

Fig. 2 is a cross section of the sprayer shown in Fig. 1, taken by line A—A'.

Fig. 3 is a second embodiment of my sprayer, shown partially in section.

Fig. 4 is a frontal view of the spraying end of sprayer shown in Fig. 1.

2

Figure 5 is a cross section of a preferred plug for use in the sprayer.

As it will be seen in Figs. 1 and 2, the atomizer I invented comprises an external cylinder 1 into which cylinder 2 of the pump is eccentrically fixed.

Into cylinder 2, a piston acted by rod 4 and handle 5 may run. Cylinder 2 is closed at both ends by walls 6 and 7. Cylinder 1 is closed at both ends by walls 8 and 9. Pump cylinder 2 is shorter than cylinder 1 and thus affords a free space between walls 6 and 8. A wall 10 partially surrounds wall 6 of cylinder 2 (see Fig. 2) forming a chamber 11 at one end of cylinder 1. This chamber 11 communicates with the space comprised between cylinder 1 and cylinder 2, through an unclosed space or opening 22. On the top of chamber 11 an opening 16, to fill the atomizer with liquid, has been provided. Into chamber 11, a second chamber 12 is fixed. Chamber 12 has an inner tube 13 extending from its bottom upwards, thus communicating chamber 11 with chamber 12. A second tube 14 extends from near the bottom of chamber 12 to the proximity of the opening of tube 15, by which air pumped by piston 3 in cylinder 2 is expelled. A cover for protecting pipe 14 may be screwed or otherwise secured on the edge 17 of cylinder 1 when the atomizer is not in use.

A preferable shape of plug to close opening 15 is shown in Fig. 3. It comprises a hollow body 18 (that may adjust into opening 16) fixed to a disk 19. The hollow body 18 contains a floater 20 (made from cork or any suitable material) secured on a pin 21 traversing disk 19 and the bottom of hollow body 18. This kind of plug prevents liquid in cylinder 1 from pouring out and simultaneously permits air entering into said cylinder; but any kind of plug permitting air into said cylinder and preventing its pouring out may also be used.

The pump comprises the known necessary valves, which as being obvious have not been shown in the drawings.

The operation of the atomizer is as follows: The liquid to be atomized is fed through opening 16 into chamber 11. A part of it fills chamber 11 and another part flows into cylinder 2 through space 11. By actioning handle 5 air under pressure is expelled through tube 15; thus liquid is taken out from chamber 12 through pipe 14 and atomized. The fall of the liquid level in chamber 12, creates a depression or vacuum in this chamber; consequently the air pressure prevailing in chamber 11 being greater than that

in chamber 12, the liquid in chamber 11 is forced into chamber 12 through tube 13. When chamber 12 is emptied, it may be refilled by simply inclining the atomizer down, so as to permit liquid in cylinder 1 to flow into chamber 11 through opening 22.

The embodiment shown in Fig. 4 differs from the atomizer shown in Fig. 1 only in that chamber 12', instead of being placed into chamber 11, is placed externally and secured to wall 8. Pipe 13', instead of being straight, as pipe 13 is, is curved. Pipe 14' is straight instead of being curved as pipe 14, used in the embodiment shown in Fig. 1. Wall 10 is substituted by a semi-circular plate 10'.

Chamber 12 is externally fixed on wall 8, as shown in Fig. 5. It is obvious that external chamber 12' may have any shape other than that shown in Fig. 5.

The atomizer shown in Fig. 4 operates in the same way that atomizer of Fig. 1 does. Once a vacuum occurs in chamber 12', the atmospheric pressure prevailing in chamber 11 forces the liquid into chamber 12' through pipe 13'.

Both of the shown embodiments present particular advantages. In embodiment of Fig. 1 pipes 14 and 15 are protected by the cover screwed on edge 17; and this cover also prevents liquid eventually dropping from pipe 14 from pouring out the atomizer. The atomizer shown in Figs. 4 and 5 is more easily manufactured, and more cheaply, than atomizer of Fig. 1.

It is obvious that the atomizer I have described may be modified and improved within the province of my invention. They may be of any suitable shape other than cylindrical; the size of chamber 11 may be modified; the shape and size of chamber 12 may be also altered; the size of space 22 may be varied, etc.

Having now described my invention, what I claim as being my exclusive property is:

1. A manually operated sprayer for liquids comprising a cylindrical casing, a partition extending across and closing one end of said casing, a cap mounted on and closing the opposite end of said casing and having an opening provided therethrough, a cylindrical pump casing positioned within, spaced from the side and bottom walls of and connected to the interior top

of said first casing, a piston slidably mounted in said pump casing, a plug for one end of said pump casing having an opening therethrough, a rod connected at one end to said piston and slidably extending through said cap and plug openings, a plate closing the opposite end of said pump casing and having an opening therethrough, a tube connected to said pump plate opening and extending through said casing partition, a semi-circular partition extending laterally within said first mentioned casing and across the lower half of said casing adjacent said pump plate leaving a fluid passage above said partition, a chamber for liquid connected to said first mentioned casing, an inlet tube extending into the upper interior portion of said chamber and into the lower interior portion of said first casing between said casing partition and said semi-circular partition, an outlet tube extending from the lower interior portion of said chamber outwardly with its open end beneath the open end of said pump tube and said first mentioned casing having a filling opening for fluid.

2. A manually operated sprayer for liquids as claimed in claim 1 wherein said chamber is positioned within said first mentioned casing between said casing partition and said semi-circular partition and said outlet tube extends through the side of said chamber and said casing partition.

3. A manually operated sprayer for liquids as claimed in claim 1 wherein said chamber is mounted on the external face of said casing partition and said inlet tube extends through the lower side wall of said chamber and bottom portion of said casing partition into the interior bottom of said casing.

CONSTANTINO LILIENTHAL.
